(57) CLAIM

I claim the ornamental design for a leggings with attached skirt, as shown and described.

DESCRIPTION

FIG. 1 is a front perspective view of the leggings with attached skirt;

FIG. 2 is a rear perspective view of the leggings with attached skirt;

FIG. 3 is a front view of the leggings with attached skirt;

FIG. 4 shows a rear view of the leggings with attached skirt;

FIG. 5 shows a first side view of the leggings with attached skirt;

FIG. 6 shows a second side view of the leggings with attached skirt;

FIG. 7 shows a top view of the leggings with attached skirt; and,

FIG. 8 shows a bottom plan view of the leggings with attached skirt.

The portions of the leggings with attached skirt shown in broken lines form no part of the claimed design.

1 Claim, 4 Drawing Sheets
